PACKAGE STACKING APPARATUS
Emil T. Reda, Baltimore, Md., assignor to Schluderberg-
Kurdle Co., Inc., Baltimore, Md., a corporation of
Maryland
Filed June 10, 1965, Ser. No. 462,953
7 Claims. (Cl. 214—6)

ABSTRACT OF THE DISCLOSURE

An apparatus which is adapted to receive successive packages as they are discharged from an article packaging machine and stack them one upon the other in a vertical column. As successive packages are received they are delivered to an elevator mechanism which raises them up and deposits them on a stack supporting means. Successive packages are inserted under the packages previously deposited on the stack supporting means.

In accordance with the invention, the stacking apparatus, which is adapted to be bolted or otherwise connected to the discharge end of an article packaging machine, comprises a bed-plate which is mounted upon the upper end of a vertically disposed supporting frame. A pair of similar opposed transversely spaced package stacking elements, between which successive packages are stacked in a column, are secured to and extend upwardly from the rear end of the bed-plate. An elevating mechanism by which successive packages, delivered to the apparatus from the article packaging machine, are raised up between the holding elements is provided. The elevator mechanism comprises a flat rectangular platform which is secured to the upper ends of a pair of vertically disposed rods which are slidably mounted in suitable bushings secured to the under side of the bed-plate. The lower end of the rods are adapted to be engaged by a pair of cams which are secured on a cam shaft rotatably mounted below the bed-plate. The rods are adapted to be moved up and down, and with them the elevator platform secured thereto, by the cams as the cam shaft is rotated. The cam shaft is adapted to be connected to and driven from the power shaft of the associated packaging machine in timed relation to the discharge conveyor thereof by which successive packages are delivered from the packaging machine onto the elevator platform of the stacking apparatus. Opposed spring loaded stack supporting means, which are yieldingly biased inwardly toward each other, are provided at each side of the elevator platform. Packages delivered onto the elevator platform are raised up thereby between the opposed supporting means to a point slightly thereabove. As a package is being moved upwardly past the yieldingly biased supporting means, it forces them outwardly thereby permitting the moving of packages up beyond the supporting means. As soon as a package has been moved past the supporting means the supporting means returns to its inner at rest position. Then as the elevator platform is lowered the package thereon is lowered down onto and held by the supporting means. Each successive package, as it is delivered onto and raised up by the elevator platform will engage the next previously delivered package, which is then resting on the supporting means, raise it up, and assume its place on the supporting means. In this manner successive packages delivered from the packaging machine are stacked in a column between the stacking elements. Means are also provided by which packages are urged rearwardly into the stacking elements as they are raised up by the elevator mechanism.

The principal object of the invention is to provide an apparatus which is adapted to be associated with a pack-

2

aging machine and is operative to automatically stack successive packages discharged from the packaging machine into a column to facilitate the handling thereof when packing them into cartons.

5 Another object of the invention is to provide an apparatus of the aforesaid character which is of simple sturdy construction, is very efficient in operation, and is relatively inexpensive to manufacture.

Having stated the principal objects of the invention 10 other and more specific objects thereof will be apparent from the following specification and the accompanying drawing forming a part thereof in which:

FIGURE 1 is a view in side elevation showing a package stacking apparatus, constructed in accordance with 15 my invention, connected to the discharge end of a packaging machine;

FIG. 2 is a front elevation of the package stacking apparatus shown in FIG. 1;

FIG. 3 is a fragmentary longitudinal section taken on 20 the line 3—3 on FIG. 2;

FIG. 4 is a fragmentary transverse section taken on the line 4—4 on FIG. 3;

FIG. 5 is a horizontal section taken on the line 5—5 on FIG. 2;

25 FIG. 6 is an enlarged fragmentary detail section taken on the line 6—6 on FIG. 1 showing the package supporting mechanism in normal stack supporting position;

FIG. 7 is a view similar to FIG. 6 showing the package supporting mechanism in the position it is moved to as 30 successive packages are raised up beyond the supporting mechanism by the elevator mechanism;

FIG. 8 is a detail perspective view of one of the side frames;

FIG. 9 is an enlarged detail horizontal section taken 35 on the line 9—9 on FIG. 1;

FIG. 10 is a fragmentary detail section showing an adapter which is removably mounted on the apparatus to accommodate it for stacking smaller packages; and

40 FIG. 11 is a perspective view of a package of the wallet type for which the apparatus as illustrated herein is especially adapted for stacking.

Having generally described the construction and operation of the stacking apparatus of the invention it will now be specifically described in connection with the drawing by the use of reference characters in which the numeral 1 indicates a horizontally disposed rectangular bed-plate, which is secured to the upper ends of a plurality of vertically disposed legs 2, and is provided with an annular down-turned flange 3. One of the legs 2 is secured to the bed-plate 1 at each corner thereof, and the fore and aft legs at each side of the bed plate are connected together by a horizontally disposed connecting plate 4.

55 A pair of transversely spaced opposed similar side frames, 5 and 6, are secured to the bed-plate 1, one adjacent each side thereof, and extend vertically upwardly therefrom. As shown herein, each of the side frames 5 and 6 is formed from a flat metal sheet, and each comprises a horizontal base section 7 and a vertical side section 8 which are connected together at the forward ends thereof by a triangular plate 9. The rear end of the side section 8 is provided with an integral elongated relatively narrow co-planar upwardly extending section 10, having an inwardly extending flange 11 along the rear edge thereof and an outwardly extending flange 12 along the forward edge thereof, which sections 10 constitute stacking elements between which packages are adapted to be stacked one above the other. The side section 8 is also provided with an integral short relatively narrow arcuate section 13 which extends rearwardly and outwardly from the rear edge thereof for a purpose to be described hereinafter. The lower end of the inturned

flange 11 terminates at the upper edge of the arcuate section 13, as shown in FIG. 3, to permit the passage of packages thereunder.

The side frame 5 is permanently secured in fixed position to the bed-plate 1, adjacent the back side thereof, by bolts 15 which are inserted through aligned apertures in the bed-plate 1 and in the base section 7 of the frame 5, and the side frame 6 is adjustably secured to the bed-plate 1, adjacent the front side thereof for transverse adjustment thereon, by bolts 16 which are inserted through a pair of apertures in the base section 7 of the frame 6 and aligned elongated slots 17 in the bed-plate 1. A wedge shaped spacer 18 is interposed between the base sections 7 of each of the side frames 5 and 6 and the bed-plate 1 to impart a slight rearward tilt to the side frames 5 and 6.

An angle bracket 19 is secured to the outer surface of the side sections 8 of the side frame 5 at the upper forward corner thereof, and a similar angle bracket 20 is similarly secured to the side section 8 of the side frame 6. An angle iron bar 21, which is secured to and between the side frames 5 and 6, is fixedly connected, at one end thereof, to the bracket 19 by a bolt 22 which extends through aligned apertures in the bar 21 and bracket 19; and is connected, at the other end thereof, to the bracket 20 by a bolt 23 which extends through an aperture in the bracket 20 and an elongated slot 24 in the end of the bar 21 thereby permitting transverse adjustment of the side frame 6. The rear ends of the side frames 5 and 6 are similarly connected together by a pair of angle bars 25 and 26, one of which 25 is connected to and between the upper ends of the upwardly extending sections 10 of the side frames, and the other of which 26 is connected to and between the side sections 8 of the side frames at the lower ends of the flanges 11.

An elevator mechanism, generally indicated by the numeral 30, is provided for raising packages, successively delivered to the apparatus from a packaging machine, up between the upwardly extending stacking elements 10 of the side frames 5 and 6. The elevator mechanism 30 comprises a rectangular platform 31, which is disposed above the bed-plate 1 between the side frames 5 and 6, and onto which packages are successively delivered. The platform 31 is secured to the upper ends of a pair of spaced parallel vertically disposed rods 32 which are slidably mounted in bushings 33 secured to the underside of the bed-plate 1. A coiled spring 34 is disposed about each of the rods 32 between the bushings 33 and collars 35 secured to the lower ends of each of the rods 32. The rods 32, and with them the platform 31, are adapted to be raised up from the normal at rest position by a pair of cams 36 which engage under the sleeves 35, and to be returned back to their normal at rest lower position by the springs 34. The cams 36 are secured to a transversely extending shaft 37 which is rotatably mounted in suitable bearings 38 carried by the connecting plates 4. The cams 36 are adapted to raise the rods 32 and platform 31 secured thereto at each revolution of the shaft 37, and are so constructed and arranged as to provide a dwell in the movement of the rods and platform in their lowermost positions.

A stack supporting mechanism, generally indicated by the numeral 40, onto which successive packages are deposited as they are raised up by the elevating mechanism 30, is provided. The supporting mechanism 40 comprises a pair of similar opposed seating devices 41 and 42, one of which, 41, is mounted on the side frame 5, and the other of which, 42, is mounted on the side frame 6, and are yieldingly biased inwardly toward each other. Each of the devices 41 and 42 comprises a horizontally disposed shaft 43 which is rotatably mounted in a pair of spaced bearing brackets 44 which are secured to and extend outwardly from the outer surface of one of the side sections 8 of the side frames 5 and 6. A plurality of longitudinally spaced similar detents 45 are mounted on and secured to the shaft 43 opposite apertures 46 in the side section 8. Each of the detents 45 comprises a hub 47, which is se-

cured on the shaft 43, and a horizontally disposed seating section 48 on which the lowermost package of a stack of packages is adapted to be seated. The seating section 48 extends inwardly through the associated aperture 46, in the side section 8 of the side frame, with the inner end thereof connected to the hub 47 by a downwardly and outwardly inclined connecting section 49. The outer end of the seating section 48 is provided with an upward extension 50 which is adapted to engage the outer surface of a side section 8 and thereby limit the inward movement of a detent 45 through an aperture 46. A coiled compression spring 51, by which the detent is yieldingly biased inwardly through the aperture 46, is interposed between the extension 50 and a bracket 52 which is secured to the outer surface of the side section 8 in outwardly spaced relation thereto.

The stacking apparatus is provided with a pair of spaced parallel rearwardly extending arms 55 by which the apparatus is adapted to be connected by bolts 56 to the discharge end of a packaging machine generally indicated by the numeral 57. A pair of transversely extending spaced parallel supports 58 are connected to and between the arms 55. A plurality of longitudinally extending spaced parallel rails, on which successive packages delivered from the packaging machine 57, are delivered to the elevator platform 31, are mounted upon the supports 58. The forward ends of the outermost rails 59 terminate adjacent the forward end of the platform 31 along the sides thereof; and the forward ends of the intermediate rails 60 terminate adjacent the rear end of the platform 31.

The packaging machine 57 is provided with a conveyor 61 by which successive packages are discharged therefrom onto the rails 59 and 60. The conveyor 61 is driven from a shaft 62 which in turn is driven by a motor 63 through sprockets 64 and 65, which are secured to the motor shaft 66 and the conveyor drive shaft 62 respectively, and a connecting chain 66. The elevator cam shaft 37 is driven in timed relation to the movement of the conveyor 61 through sprockets 67 and 68, which are secured to the elevator cam shaft 37 and the conveyor drive shaft 62 respectively, and a connecting chain 69. A chain tightener, which comprises a meshing sprocket 70 mounted on a stud 71 carried by an arm 72 secured to one of the legs 2, is provided for taking up any slack in the chain 69.

In operation packages are successively delivered from the packaging machine 57 onto the rails 59-60 during dwells in the movement of the platform 31 in its lowermost normal position. As each package is delivered onto the rails 59-60 it moves the previously delivered packages forwardly the length of one package until the rails are filled with packages between the rear end of the platform 31 and the discharge end of the conveyor 61, after which each successive package delivered forces the foremost package in the line of packages forwardly over the platform 31 in position to be engaged by the platform 31 on the next upward movement thereof. The opposed rearwardly and outwardly extending arcuate extensions 13 cooperate with each other to center the packages between side frames 5 and 6 as the packages are delivered therebetween. A pair of vertically disposed elongated rectangular plates 75 which are secured to the cross bar 21 in spaced parallel relation to each other and extend downwardly therefrom, are provided to limit the forward movement of the packages and properly position them over the platform 31.

As the packages are moved upwardly on the platform 31 between the seating devices 41 and 42 they engage the inclined sections 49 of the detents 45 and force them outwardly through the apertures 46 against the resistance of the springs 51. The platform 31 raises each package up beyond the detents 45 after which the detents are returned to their normal positions by the springs 51. Then as the platform 31 is lowered it deposits the package thereon on the seating sections 48 of the detents 45. As

successive packages are raised up on the platform 31 they engage the package previously deposited on the seating sections 48 and raise it and the packages thereabove upwardly along with it, and then lower them all downwardly until the package on the platform is deposited on the seating sections 48. As successive packages are raised up by the platform they are stacked in a vertical column between the stacking elements 10 with the rear sides thereon in engagement with the inturned flanges 11 of the stacking elements.

In order to insure the even stacking of the packages, one above the other, the stacking element 10', which extends upwardly from the side frame 6, is provided with a resiliently mounted elongated narrow strip 76 which is parallel thereto and coextensive therewith, and is spaced outwardly from the inner surface of the element 10'. The strip 76 is secured to the inner ends of a plurality of bolts 77 which are slidably mounted in bushings 78 secured to the outer surface of the element 10'. Coiled springs 79, which are disposed about the bolts 77 between the strip 76 and the inner surface of the stacking element 10', yieldingly bias the strip 76 toward the opposed stacking element 10. The strip 76 will therefore yieldingly force the far sides of the packages against the inner surface of the stacking element 10. The position of the strip 76 with respect to the element 10' and the pressure exerted thereby under the influence of the spring 79 may be adjusted by means of nuts 80 threaded onto the free ends of the bolts 77.

When it is desired to adapt the apparatus for stacking smaller packages of the same configuration but of lesser length and width, the bolts 16 and 23 are loosened and the side frame 6 moved towards the side frame 5 in accordance with the width of the smaller packages. And in order to properly position the smaller packages over the platform 31 an adapter 81 is removably secured to the upper end of each of the stop plates 75 by set screws 82.

From the foregoing it will be apparent to those skilled in this art that I have provided a very simple and effective apparatus for accomplishing the objects of the invention.

It is to be understood that I am not limited to the specific construction shown and described herein as various modifications may be made therein within the spirit of the invention and the scope of the appended claims.

What is claimed is:

1. A stacking apparatus of the character described by which successive packages delivered thereto from a packaging machine are stacked one upon the other in a vertical column, said apparatus comprising: a flat rectangular horizontally disposed bed-plate which is mounted upon the upper end of a vertically disposed supporting means, a pair of opposed parallel transversely spaced similar side frames which are secured to said bed-plate and extend upwardly therefrom; a pair of opposed similar package stacking elements which are secured to and extend upwardly from each of said side frames; a pair of opposed horizontally disposed similar stack supporting devices one of which is pivotally mounted on each of said side frames and is yieldingly biased outwardly from the inner surface thereof; a vertically reciprocal elevator mechanism by which successive packages delivered thereto are raised up beyond said supporting means between said stacking elements and are then lowered onto said supporting means; and means by which successive packages are delivered to said elevator mechanism; each of said stack supporting devices comprising a horizontally disposed shaft which is secured to the outer surface of each of said side frames, and a plurality of horizontally spaced detents which are mounted on said shafts; each of said detents comprising, a hub which is rotatably mounted on said shaft, a horizontal section which is disposed above said hub and extends inwardly through an aperture in the

said side frames, a downwardly and outwardly inclined cam surface which is connected between the inner end of said horizontal section and said hub, spring means by which said detent is yieldingly biased outwardly through said aperture, and a stop by which the inward movement of said detent through said aperture is limited; and said elevator mechanism comprising a platform which is disposed above said bed-plate between said side frames in alignment with the said detent means mounted on said side frames, said platform being secured to the upper ends of a pair of transversely spaced vertically disposed rods which extend upwardly through said bed-plate and are slidably mounted in a pair of guides secured to and extending downwardly from said bed-plate, a transversely disposed shaft which is rotatably mounted in said supporting frame, a pair of cams secured on said shaft in position to engage the lower ends of said rods, said cams being operative upon the rotation of said shaft to raise and lower said rods and the said platform secured thereto to a dwell in the movement thereof at the lower limit of movement thereof, and means by which said shaft is adapted to be rotated in timed relation to the operation of a packaging machine with which the stacking apparatus is associated.

2. A stacking apparatus as defined by claim 1 in which one of said side frames is adjustably secured to said bed-plate for lateral adjustment thereof with respect to the other of said side frames to accommodate said apparatus for stacking different width packages.

3. A stacking apparatus as defined by claim 1 in which stop means is provided by which the inward movement of successive packages delivered to said elevator mechanism is limited.

4. A stacking mechanism as defined by claim 3 in which said stop means is mounted upon a transversely extending bar which is secured to and between the forward ends of said side plates.

5. A stacking apparatus as defined by claim 1 in which said stacking elements are adapted to engage the side and rear edges of packages delivered therebetween by said elevator mechanism.

6. A stacking apparatus as defined by claim 5 in which one of said stacking elements is provided with a resiliently mounted vertically disposed elongated strip which is adapted to yieldingly engage one side edge of packages disposed between said elements and force the other side edge of the said packages disposed between said elements into engagement with the other of said elements.

7. A stacking apparatus as defined by claim 1 in which said side frames are provided with rearwardly and outwardly extending arcuate extensions which cooperate with each other to center successive packages with respect to said side frames as the said packages are delivered to said elevator mechanism from an associated packaging machine.
